J. W. CULBERTSON, OF RICHMOND, INDIANA.

Letters Patent No. 89,030, dated April 20, 1869.

IMPROVED CATARRHAL SYRINGE.

The Schedule referred to in these Letters Patent and making part of the same.

To all whom it may concern:

Be it known that I, J. W. CULBERTSON, of Richmond, in the county of Wayne, and State of Indiana, have invented a new and improved Catarrhal Syringe, for injecting fumes, liquids, or atmospheric air, into the nasal-passages, pharynx, or middle ear; and I do hereby declare that the following is a full and exact description thereof, reference being had to the accompanying drawings, making a part of this specification.

My invention relates to an improved construction of the nozzle of a syringe, whereby it is especially adapted to the uses for which it is designed; and also, in attaching the nozzle directly to an elastic bag, without the intervention of a flexible tube, thereby rendering the instrument more convenient, and reducing the cost of its manufacture.

To enable others skilled in the art to make and use my invention, I will proceed to describe the same, with reference to the drawings, in which—

Figure 1 is a perspective view of my improved syringe.

Figure 2 is a longitudinal section of the same, and

Figure 3 is likewise a longitudinal section, made at right angles with the section represented in fig. 2.

The nozzle is oval in form, and is provided with a central perforation, that emits a single jet, which is protected by the concavity in the nozzle, as shown by the drawings.

By this arrangement, the jet can be made more

penetrating and effective than it would otherwise be, thereby peculiarly adapting it to the uses hereinafter enumerated.

The nozzle A is secured directly in the cap E of the elastic bag B, without the intervention of a flexible tube. By means of this arrangement, the greatest simplicity and durability are combined with convenience and economy of construction.

The nozzle fills one side of the nostril. Pressing on the other side with the finger prevents the escape of whatever is used, and the amount of force required is regulated by compressing the bag.

In this manner the middle ear can be inflated. If the Eustachian tube is closed, it can be opened by a forcible jet of air from this instrument.

By compressing the bag, and plunging the nozzle in solutions, the nasal-passages and pharynx may be flooded and cleansed, and remedies directly applied by the patient himself.

Having thus fully described my said invention, What I claim, and desire to secure by Letters Patent, is—

The enlarged oval nozzle A, having a central perforation for the jet, and provided with a concavity at the end, as and for the purpose set forth.

J. W. CULBERTSON.
